Attorney

UNITED STATES PATENT OFFICE.

WILLIAM W. ESSICK, OF READING, PENNSYLVANIA.

LENS-BLOCK.

1,268,556.

Specification of Letters Patent. Patented June 4, 1918.

Continuation of application Serial No. 86,182, filed March 23, 1916. This application filed November 20, 1916. Serial No. 132,348.

To all whom it may concern:

Be it known that I, WILLIAM W. ESSICK, a citizen of the United States, residing at Reading, in the county of Berks and State of Pennsylvania, have invented certain new and useful Improvements in Lens-Blocks, of which the following is a specification.

This invention relates to improvements in the art of mounting lens blanks on lens-blocks for surface grinding, and the object in the present instance is to provide means for accurately and rapidly placing the blanks on the lens-block.

The present invention is intended as an improvement on that particular feature described in Letters Patent No. 1143895, issued to me under date of June 22, 1915, in which I make provision for placing the blanks on the facets, and which consists in forming "a groove in the raised lens holder facet which the operator can readily see in setting the lens and which enables him to accurately and quickly place the latter."

It is evident that with the above method, the degree of accuracy and the speed with which the blanks are placed, depends to a great extent on the skill and carefulness of the operator.

It is my object in the present invention to provide a simple and positive means for accurately and rapidly placing the blanks even though the operator be both unskilled and careless.

My invention consists in providing a lens-block with a series of registration points, so arranged with relation to the facets or "spots" on which the lens blanks are to be placed, that when a suitable lens blank positioning device is placed in register with one or more of these registration points, the position of the lens blank with relation to the "spot" will be easily and accurately determined.

The invention will apply to lens-blocks having plain or smooth surfaces as well as to those having the facets.

In the present instance I have shown the lens-block formed with raised lens-facets, and, in certain relation with each facet I provide one or more registering points, preferably in the form of indentations in the lens-block coating, adapted to receive registering projections on a lens blank positioning device, so that when the said device is thus placed in register with the block, the

lens blank may be laid on the facet and moved forward until its edge contacts with the concaved surface of the device, which will bring the optical center of the lens blank accurately in position over the center of the facet.

It is to be understood that this method of blocking lens blanks is applicable to those blanks which have been finished as to their outer edges before being mounted on the lens-block for surface grinding, and the economy of this method of accurately positioning them will be appreciated for the reason that every blank is ground with the optical center at the exact center of the lens, thus overcoming the necessity of reshaping or reducing the blank in size after grinding, as would be the case were the optical center not so located. The great saving in product due to this method of grinding is also evident.

In the drawing forming a part of this application:—

Figure 1 is a plan view of a portion of a lens-block showing several of the lens-facets and the relative positions of the registering points.

Fig. 2 shows an elevation and Fig. 3 a plan view of a simple form of lens blank positioning device.

Fig. 4 is a sectional view taken on the line X—X of Fig. 1.

The numeral 1 designates the lens-block and 2 the lens holding facets or "spots" on its surface.

In certain relation with each facet, that is, at a certain distance from the center of each facet, I form one or more indentations in the surface of the block, as indicated by 3.

These indentations will serve as registering points for any suitable lens positioning device and will positively determine the proper position for placing the lens blanks on the facets or "spots."

The numeral 4 designates a preferred form of lens blank positioning device, which consists of a handle member 5, a body portion 6 and a pair of registering points in the form of projections 7, depending from the under side of the body portion; this body portion is preferably formed with a concaved surface 8 against which the edge of the lens blank is placed in the act of mounting it on the facet.

This device 4 is portable, and in use it is moved from one facet to another as the blanks are to be placed.

The registering projections 7 are inserted 5 in the indentations 3, and when these points are in register the concaved contact surface 8 of the device will be in proper position relatively to the facet center. The lens blank is then placed on the surface of the 10 facet and its edge is pressed against the concaved surface 8 of the device, which will bring the optical center exactly over the center of the facet, a predetermined result, and the blank is then seated securely thereon by pressure, as usual. The device is then 15 moved to an adjoining facet and the operation repeated, and when the surface of the lens-block is covered with blanks they are ready for surface grinding in the usual 20 manner.

It is evident that both accuracy and speed are assured, even though the operator exercise the minimum of skill and care.

It will be understood that inasmuch as 25 each facet or "spot" is accurately located relative to the focal axis of grinding, it is of vital importance that the optical center

registers exactly with the center of the facet, and to accomplish this with ease, accuracy and rapidity has been my object in the 30 present invention.

It is evident that a single elongated depression 9 may be provided in the lens block to serve as a registering point, instead of a plurality of indentations (as shown in Fig. 35 1) or that other similar positioning means as between the device and the facet may be employed without departing from the spirit of my invention.

The lens-block being a substantially hemi- 40 spherical metal shell provided with a coating of pitch in which the facets and the registration points are formed when the coating is placed on the block.

What I claim is:—

A lens block having facets and a plurality of contact walls in fixed relation to each facet, and a lens blank positioning device having members adapted to seat against said walls and having a contact surface 50 adapted to engage a lens blank.

In testimony whereof I affix my signature.

WILLIAM W. ESSICK.
